Application June 9, 1933, Serial No. 675,138
In Australia June 9, 1932

6 Claims. (Cl. 194—2)

The main object of the present invention is to provide an efficient machine for vending certificates in which a predetermined number of share tickets are being sold, but such machine must necessarily involve a large number of features in order to make it simple to operate and also to ensure that it shall be difficult if not impossible to fraudulently manipulate without the detection of the person guilty of such fraudulent manipulation.

A feature of the invention is the exhibition of the certificate in which a predetermined number of share tickets are being sold, the movement of that certificate to an obscured position when the predetermined number of share tickets are sold, the movement of another certificate to its place and the marking of the certificate in which the share tickets have been sold with a word such as "Sold" to indicate it is a certificate in which a number of persons are share holders or holders of share tickets. Another feature is a means for indicating the number of share tickets that have been sold in the certificate exhibited.

Another feature of the invention is the provision of means whereby the use of a spurious coin may be identified with a particular share ticket issued to a person whose signature and address is retained within the machine.

Another feature of the machine is that each person purchasing a share ticket must write his or her application or name and address upon a tape or paper band that is retained within the machine. Another feature is a desk having a glazed cover and over which the tape or paper band is moved as each share ticket is issued. Yet another feature is that means are provided for moving the cover to enable the intending purchaser to write his or her application and the replacement of the cover during the issue of each ticket.

The invention embodying these and other features will now be fully explained in the following description wherein reference will be made to the accompanying drawings in which:—

Figure 1 is a front elevation of the apparatus, showing in dotted lines the coin operated release to enable the writing desk cover plate to be withdrawn and thus uncover the writing desk.

Figure 2 is a part front elevation showing the position of the cover plate when it has been released by the insertion of coin and actuated by a spring.

Figure 3 is a perspective view of the writing desk cover plate viewed from the interior of the machine.

Figure 4 is a sectional front elevation of the apparatus the front of the casing and the share ticket elevating delivery chute being removed.

Figure 5 is a sectional elevation, taken on the line A A of Figure 6, the view being taken in the direction of arrow and showing the cam operated bell crank for withdrawing the certificate in which a predetermined number of share tickets have been issued and also the cams for operating the share ticket stamps.

Figure 6 is a sectional plan with the cover removed.

Figure 7 is a sectional elevation taken on the line B B of Figure 6, the view being taken in the direction of the arrow, and illustrating the writing desk and paper roll.

Figure 8 is a sectional elevation taken on the line C C of Figure 6, showing the coin in a position to enable the machine to be operated by the handle which is shown in dotted lines for the purpose of clearness.

Figure 9 is a sectional elevation similar to Figure 8 but with the operating handle at the completion of its stroke, a portion of the handle being shown in dotted lines for the purpose of clearness.

Figure 10 is a sectional elevation taken on the line D D of Figure 6 showing the means for stamping each of the certificates each time a share ticket is sold and means for withdrawing the certificate into a receptacle when a predetermined number of share tickets have been issued.

Figure 11 is a fragmental sectional elevation taken on the line E E of Figure 6, showing the share ticket magazine and means for ejecting a share ticket each time the operating handle is manually operated, the operating handle or lever being shown for the purpose of clearness.

Figure 12 is a sectional elevation taken on the line E E of Figure 6 and showing the position of the parts when the operating handle (which is shown for the purpose of clearness) has been returned to its normal position.

The mechanism of the machine is housed in a suitable metal casing 21 of any convenient shape and any portion or side thereof may be hinged or provided with a door or doors to give access to the interior thereof. The casing 21 is provided with a slot 22 (Figures 1 and 2) through which the operating handle 23 is moved and a coin slot 24 through which a coin 25 passes into a coin chute 26.

The coin passes from the coin chute 26 into an approximately V shaped throat 27 (Figures 8 and 9) formed upon a coin transferring arm 27a for the purpose of transferring it from a position at the bottom of the chute 26 to the upper portion 55

of the coin exhibiting receptacle 26a. The coin in its passage through the coin chute 26 is caused to impinge against one end of a spring controlled catch 28 forcing it outwardly, the other end 28a 5 of the catch 28 disengages it from another catch 29 forming one end of a cover plate 30 adapted to slide in guides 31 that are secured at the sides of a writing aperture 32 formed in the casing 21. The cover plate 30 is actuated by a spring 33 in 10 tension, one end of which is secured to the cover plate 30 by a pin 34 the other end being secured by a pin 35 fixed to the wall of the casing 21, so that when the catch 29 is released the spring 33 will withdraw the cover plate and expose the 15 aperture 32. The coin 25 having fallen from the coin chute 26 into the V shaped throat 27 in the coin transferring arm 27a (Figure 8) the operating handle 23 (the lower end of which and the coin transferring arm 27a are rigidly secured upon 20 a main shaft 36) may now be operated. The ends of this shaft 36 are rotatably mounted in bearings 37 and 37a formed in an end of the casing 21 and a division plate 38 respectively. The operating lever 23 is provided with an extension 39 thus 25 forming a bell crank lever, the end of the extension 39 being connected to a spring 40 the other end of which is connected at 40a to the casing 21 to automatically return the manually operated lever 23 to the normal position. The 30 operating handle 23 is manually operated by pulling it forwardly and downwardly and is automatically returned to its normal position by the spring 40. Rigidly secured to the division plate 38 is a bracket 41 to which is pivotally secured at 35 42 a specially constructed inverted U shaped member or saddle 43 at each end of which is formed or rigidly secured a catch 44. Within the bend of the inverted U shaped piece 43 is rigidly secured a face cam 45. The coin transferring 40 arm (Figures 8 and 9) normally lies within the inverted U shaped piece 43 and is provided with a stop 46 projecting from each side thereof and positioned so that they will engage with the catches 44 and normally prevent the movement 45 of the lever 23. In order to release the catches 44 from engagement with the stops 46 and thus permit the operating lever to be moved and the coin 25 transferred from the bottom of the chute 26 to the upper portion of the coin receptacle 26a, 50 the coin in moving with the transferring arm 27a through the U shaped piece 43 will impinge against the face cam 45 and thereby raise the catches 44 on the pivot 42 and permit the stops 46 to pass beyond their respective catches 44. When the 55 coin passes the face cam 45 the inverted U shaped member 43 and the catches 44 therein will gravitate to their normal positions and be maintained by flats 47 formed upon the underside of the rear ends of the catches 44 which will then rest 60 upon the upper surface of the bracket 41. The completion of the downward movement of the operating lever 23 will bring the coin transferring arm to the position shown at Figure 9 when the coin will fall from the throat 27 into the upper 65 part of the coin receptacle 26a onto a trap member 48 having an inclined surface 48a down which it will slide until it strikes the inner face of a glazed aperture 49 in the casing 21 and through which latter the coin is visible exteriorly 70 of the casing. The trap member 48 is pivoted at 50 to the sides of the coin receptacle 26a, and is maintained in its normal position with its lower edge impinging against the glazed face of the aperture 49 by means of a rod 51 one end of which 75 is pivoted at 51a to the trap member 48, the other

end being loosely secured in a slot formed near the upper end of a plate 52, the lower end of which is hingedly secured at 53 to the base of the casing 21. The rod 51 is maintained in a forwardly thrust position by means of a spring 54 in tension, one end of such spring being secured at 55 to a side of the coin receptacle the other end being secured at 56 to the rod 51. The rod 51 is provided with a collar 57 and a transverse pin 58 to maintain its connection with the plate 52. The 10 object of this arrangement is to provide a means whereby each coin inserted in the machine will be visible through the glazed aperture 49 as a deterrent to fraud but will be removed therefrom before the next coin inserted in the machine is 15 transferred to the upper portion of the coin receptacle 26a. It has been shown how the coin is transferred to the upper part of the receptacle 26a and it will now be shown how it is removed therefrom before the next coin enters. A cam 20 lever 59 is rigidly secured to the main shaft 36 at an angle to the operating lever 23 such that as the shaft 36 is partly rotated by the manual movement of the operating lever 23 the cam lever 59 will strike the upwardly projecting end of the 25 plate 52 and move it to the position shown by dotted lines at 52a (Figure 9) thereby moving the rod 51 longitudinally in a rearward direction and thus causing the trap member 48 to move on its pivot 50 away from the glazed aperture 49 30 and permitting the coin 25 to drop to the bottom of the receptacle 26a. At this point the hinged plate 52 is released by the cam lever 59 and the spring 54 returns the trap member 48 and rod 51 and plate 52 to their normal position before 35 the coin carried by the transferring arm 27a is delivered into the upper part of the coin receptacle 26a. It will be seen, however, that the subsequent return of the cam lever 59 to its normal position would cause it to strike the plate 52 and 40 move it to the position shown by dotted lines at 52b (Figure 9) and in order to return it to its normal position in readiness for the next operation a compression spring 60 is interposed between the collar 57 and the rod 52. 45

It is an object of this invention to issue a share ticket (61) each time the operating lever 23 is manually operated and the mechanism for effecting this object is shown more particularly at Figures 11 and 12. The share tickets are 50 superimposed one upon the other within a tubular magazine 62 of rectangular shape in cross section and which may be provided with a wide slot 63 formed longitudinally throughout the entire length of one side to facilitate the positioning of the tickets therein. At the bottom of the front and rear side of the magazine 62 is a transverse slot 64 (Figure 4) the width of which is sufficient to permit a share ticket 61 to pass freely through it. The magazine is fixed in a 55 vertical position to a raised platform 65, whereon is formed or rigidly secured at one side of the magazine 62 a vertical bracket 66 to which is pivotally secured at or about its centre a rocking lever 67. To the lower end of the rocking lever 65 67 is pivotally secured one end of a link 68 from the other end of which projects laterally and below the raised platform 65 an arm 69 which terminates in a block 69a; integral with or rigidly secured to the block 69a is a stud pin 70 70 which passes upwardly through a slot 71 in the raised platform 65 and is secured to a sliding drawer plate 72 having an aperture therein to receive the lowermost ticket and adapted to be moved in the slot 64 by the rocking lever 67. The 75

upper end of the rocking lever 67 is connected by a link 73 to one end of a lever 73a the other end of which is rigidly secured to the main shaft 36 so that as the latter is partly rotated by the 5 manual operation of the lever 23 the stud pin 70 and with it the drawer plate 72 will be caused to move along the slot 64, and the lowermost share ticket 61a is thereby ejected from the magazine 62 through the slot 64 from whence 10 it enters a ticket chute 74 as shown by dotted lines in Figure 11.

The share ticket chute 74 normally lies in the inclined position shown at Figure 12 its forward end being mitred for that purpose; it is 15 pivotally secured to a bracket bearing 75 rigidly secured to the base of the casing 21, and its mitred end lies in register with an aperture 76 in the casing 21 and through which the ticket is ejected from the machine when the chute 20 is raised to the inclined position shown at Figure 12. For the purpose of raising the share ticket chute 74 from a horizontal position (Figure 11) to an inclined position (Figure 12) one end of a connecting rod 77 is pivotally secured at 78 to 25 a side of the chute 74, its other end being pivotally secured to one end of a rod 79 arranged to slide longitudinally in a guide block 80 rigidly secured to a division plate 38a, the other end of the rod 79 being provided with an anti-friction roller 81 30 adapted to contact with the face of a cam 82 that is rigidly secured to the main shaft 36. The share ticket chute 74 is supported at its rear end, when lying in a horizontal position, by one or more rubber tipped buffers 83. The manual 35 movement of the operating lever 23 causes the cam 82 to move in an anti-clockwise direction thus permitting the chute 74 to gravitate to a horizontal position in order to receive the share ticket 61a as it falls from the aperture in the draw plate 72 when the latter is pushed forward 40 as previously explained.

The certificates 84 are temporarily secured in metal holders 85 that are stacked within a magazine 86 and continually fed to the top thereof 45 by a plunger 87 which is connected to a pivoted lever 88 by means of a link 89 the lever 88 being pivotally mounted at 89a upon a bracket 90 secured to a raised base 91 at the bottom of the casing 21 (Figure 10). The lever 88 is controlled 50 by a spring 92 in tension, one end of which is secured to the lever 88 the other end being secured to the raised base 91. One side of the magazine 86 is provided with an arcuate slot 93 to permit the connecting pin 94 to be moved upwardly by the lever in order to raise the plunger 87 within the magazine. Another magazine 95 is positioned immediately behind the magazine 86 to receive the certificate holders 85 and certificates 84 therein as they are removed from the 55 magazine 86. The removal of the holders 85 and certificates 84 is effected by a spring actuated sliding arm 96. To the forward end of the sliding arm 96 is articulated at 97 a hook 98 that engages with the edge of the uppermost certificate holder 85 when it has been moved to the 60 limit of its forward movement. The movement of the hook 98 is limited in one direction by a stop 99 rigidly secured to the sliding arm 96. The sliding arm is housed in a tubular guide 100 that is 65 mounted upon and secured to a platform 101 formed at the top of the magazine 95. The rear end of the sliding arm 96 is pivotally connected at 102 to one end of a link 103 the other end of which is pivotally connected at 104 to one end 70 of a bell crank lever 105. The bell crank lever 75

105 is pivotally connected at 106 to a bracket 107 rigidly secured to a part of the casing 21. The other end of the bell crank lever 105 is provided with an anti-friction roller 108 adapted to engage with a cam 109 fixed to a shaft 110. 5

A spring 111 has one end connected to the bell crank lever 105 the other passing around a grooved wheel 112 and its extremity secured at 113 to a part of the casing 21 or any convenient fixture. The wheel 112 is partly enclosed by the casing 10 114 to the sides of which is secured the shaft 10 upon which it rotates.

It will now be shown how rotary motion is imparted to the shaft 110 and reference will be made more particularly to Figures 9 and 10. A 15 lever 115 is pivoted at or about its centre 116 to the division plate 38. Its lower end is provided with an anti-friction roller 117 and its upper end is connected at 118 to one end of a connecting rod 119 the other end of which is pivoted at 119 to 20 the outer end of a crank 121 which is rotatably mounted upon the shaft 110. One end of the shaft 110 is mounted in suitable bearings 122 (Figure 6) carried by the division plate 38 the other end being rotatably mounted in bearings 25 123 secured to the casing 21. Fixed to the shaft 110 adjacent to the crank 121 is a six-toothed ratchet wheel 124, the teeth of which are engaged by the pawl 125 that is pivotally secured at 126 to the crank 121. Motion is imparted to the lever 30 115 in order to move it from the position shown at Figure 8 to that shown at Figure 9 by a cam 127 that is fixed to the main shaft 36, each time the latter is partly rotated by the manual movement of the operating lever 23. This movement 35 of the lever 115 is transferred through the connecting rod 119 to the crank 121, pawl 125, ratchet wheel 124 to the shaft 110 which is thereby moved through an arc of 60 degrees so that each complete rotation of the shaft 110 will require six 40 manual movements of the operating handle 23 and six share tickets will be ejected from the machine.

According to the construction of the machine selected to illustrate our invention six share 45 tickets in each certificate are sold and a similar number of share tickets are issued in respect of each certificate but it will be obvious that by mechanical variations the machine could be arranged to issue any predetermined number of 50 share tickets in respect of each certificate.

The number of share tickets issued in respect of the certificate exhibited through the glazed aperture 151, is indicated by a numeral on an indicating roller as each share ticket is issued, i. e. 55 1, 2, 3, 4, 5, or 6 is shown by an indicating numeral on the indicating roller 128 that is secured to a shaft 129 which is mounted in bearings formed in brackets 130 rigidly secured to the casing 21. The roller 128 may, however, be shown "0" to "5" 60 inclusive but the share tickets issued will still be marked as explained. A sprocket wheel 131 (Figures 4 and 5) is fixed to the shaft 129 and is connected to another similar sprocket wheel 132 fixed to the shaft 110 by means of an endless 65 sprocket chain 133. The upper front portion of the casing 21 is provided with two glazed apertures 134 and 135 (Figure 1) and the roller 128 (which may be provided with six flat sides) is positioned horizontally and immediately behind 70 these glazed apertures. The share ticket indicating numerals are placed around the roller and any one of these numerals will be visible through the smaller glazed aperture 134. The remainder of the roller 128 may be used for advertising pur- 75

poses and the advertisements will be visible through the glazed aperture 135.

According to this invention as each share ticket is issued a definite marking such as "Sold" with or without the addition of a numeral will be stamped across or upon the face of the certificate exhibited through the glazed aperture 157. It will therefore be seen that each certificate will have a number of markings according to the predetermined number of certificates issued in respect of each certificate. It will now be shown how these markings are effected and how when the sale of the predetermined number (six in this case) certificates is completed the certificate is removed to a concealed position and is replaced by another.

Mounted in bearings 136 formed in brackets 137 that are rigidly secured to the platform 101 (Figures 5 and 10) is a cam roller 138. The cam roller 138 is rotated by means of a sprocket wheel 139 secured to the shaft of the cam roller 138 that is connected by an endless chain 140 to another sprocket wheel 141 fixed to the shaft 110. Six cams 142, 142a, 142b, 142c, 142d, 142e, 142f are rigidly secured to and project radially from the cam roller 138 (Figure 10); they are equally spaced longitudinally (Figure 5) and are positioned at 60 degrees from one another around the circumferential surface of the cam roller 138. Another pair of brackets 143 are secured upon the platform 101 and are provided with bearings to receive the respective ends of a shaft 145 upon which are rotatably mounted six bent levers, 146, 146a, 146b, 146c, 146d, 146e, (Figures 4 and 10) at equal distances apart. A rubber or other suitable stamp 147 is secured to the forward end of each of the bent levers 146—146e inclusive; the other ends of these bent levers are adapted to be engaged sequentially by the respective cams 142—142e inclusive, on the cam roller 138, and are each attached to the ends of springs 149, the other ends of which are secured to the platform 101. The partial rotation of the cam roller 138 will cause one of the cams 142—142e to contact with the adjacent end of its respective bent lever 146 and in rotating with the roller 138 will cause the stamping lever 146 to rotate upon its shaft 145 and carry the stamp 147 through an arc to a position shown at Figure 10 where it is pressed upon the face of the share ticket for the purpose of making the necessary mark thereon. The stamps 147 will require to be inked for each impression but an inking roller placed so as to roll over the surface of the stamp would prevent the return of the stamp to its normal position. Each is therefore provided with an arcuate guide 150 the forward end of which is fastened to the respective stamp and will move with it (Figure 10). A pair of brackets 151 are secured upon the platform 101, and to each of the upper ends thereof are secured one end of swing arms 152 the other ends being secured to the respective ends of a shaft 153. Upon the shaft 153 are rotatably mounted six inking rollers 154 each of which is separated from the next adjacent inking roller by a distance piece 155 rotatably mounted upon the shaft 153. The arcuate guides 150 impinge against the distance pieces 155 as they move with their respective levers 146—146e, and thus thrust the shaft 153 and inking rollers outwardly against the action of a spring 156 one end of which is secured to the arm or arms 152 and the other end to the respective brackets 151.

It has been shown how the certificate is stamped each time a share ticket is issued and

it will now be shown how the sliding arm 96 is caused to operate after the final stamping has been placed upon the certificate in order that the holder 85 in which the certificate is held may be removed and the underlying certificate exposed to view through the glazed aperture 157 in the casing 21. The normal position of the bell crank lever 105 is shown by dotted lines at Figure 10 and it has been explained how the shaft 110 is caused to rotate through an arc of 60 degrees each time the operating lever 23 is manually moved. The rotation of the cam 109 with the shaft 110 in the direction of the arrow will gradually thrust the anti-friction roller 108 outwardly and in doing so will cause the bell crank lever 105 to move from the position shown in dotted lines to the position shown in full lines (Figure 10). The movement of the bell crank lever will cause the sliding rod 96 to move forwardly across the face of the exposed certificate 84 to a position where the hook 98 drops into engagement with the edge of the certificate holder 85. The final part of the sixth manual movement of the operating lever 23 (after the sixth stamping on the face of the certificate 84 has been made) will bring the cam to a position where the spring 111 is free to actuate the bell crank lever 105 and its associated parts, causing it to return to the normal position and in doing so slide the holder 85 and certificate 84 therein to a position where it will drop into the magazine 95 and be concealed from view. The lever 88 actuated by the spring 92 will force the stack of certificate holders and certificates therein upwardly as previously explained, thus positioning the uppermost certificate holder and certificate therein ready for the next cycle of operation.

The upper end of the plunger 87 may be provided with a disc on which may be printed such words as "Machine Empty" so that when the last certificate has been withdrawn the words may be seen through the glazed aperture 157 to indicate to intending purchasers that the machine is not operating.

For the purpose of identifying the purchasers of share tickets each purchaser will write his or her name and address upon the portion of a roll of paper 158 which is exposed through the writing aperture 32. In order to support the writing desk 159 an inverted U shaped frame 160, (of which the writing desk 159 forms the upper limb) is rigidly secured to the division plate 38a. A pair of parallel guides 161 are secured to the writing desk 159 to form guides for the paper 158 as it passes over the desk. The roll of paper 158 is secured upon a removable shaft 162 supported by the frame 160. The paper will pass from the roll 158 over the desk 159 thence over a roller 163 when it will fall to the bottom of the casing 21. The roller 163 is secured to a shaft 164 rotatably mounted in the frame 160, the shaft 164 being provided at one end with a ratchet wheel 165. Intermittent motion is imparted to the shaft 164 by a crank 166 fixed to the main shaft 36 when the operating lever 23 is manually operated. One end of a connecting rod 167 is pivotally connected at 168 to the crank 166 the other end being pivotally connected at 169 to one end of an arm 170, the other end of which is rotatably mounted upon the shaft 164 (Figures 6 and 7). A pawl 171 is pivotally connected to the arm 170 and engages the teeth of the ratchet wheel 165. In order to grip the paper and draw it a predetermined distance from

the roll 158 a pressure roller 172 is rotatably mounted between a pair of arms 173 that are pivotally secured at 174 to the frame 160, the arms 173 being further secured together by a tie rod 175. The pressure roller 172 is caused to press against the roller 163 by means of springs 176 one end of which is secured to the respective arms 173 and the other end being connected to the frame 160.

10 It has been shown how the cover plate 30 (Figures 1, 2 and 3) automatically exposes the writing paper through the aperture 32 and it will now be shown how the cover plate is replaced during the issue of each share ticket. One end 15 of a lever 177 is fixed to the main shaft 36 and the other end is provided with an anti-friction roller 178 that is axially parallel with the lever 177. When the shaft 36 is partly rotated by the operating lever 23 it will cause the lever 177 20 to move through an arc and in doing so the anti-friction roller 178 will impinge upon a cam face 179 formed on a bracket 180 secured to the underside of the cover plate 30 (Figure 3) and cause the latter to slide against the action of the spring 33 to a position where the aperture 32 is completely closed and the catch 29 moved to a position where it will be engaged and retained in that position by the catch 28a.

25 The share tickets in the magazine 62 are 30 mounted by a loose weight 181 which will gravitate as the share tickets are removed and when the last share ticket in the final certificate within the machine is ejected from the magazine its position in the drawer plate 72 will be occupied 35 by the weight thus preventing any further movement of the drawer plate and its associated parts.

35 It will be understood that the share tickets will be marked and arranged in the proper order in 40 the machine so as to correspond with the particular certificate in respect of which it is issued. It will also be understood that the roll 158 will be so marked to correspond with markings on each share ticket so as to enable the 45 purchase of any particular share ticket to be verified.

We claim:

1. A machine for vending share tickets for certificates comprising means for exhibiting a certificate for which the share tickets are being is- 50

sued, means freed by an inserted coin for issuing a share ticket, and means for moving the exhibited certificate to a position of concealment and replacing it by another when a predetermined number of share tickets have been issued.

5

2. A machine for vending share tickets for certificates as claimed in claim 1 and comprising means for printing upon the certificate exhibited the word "Sold" or other like marking each time a share ticket is issued.

10

3. A machine for vending share tickets for certificates as claimed in claim 1, comprising a share ticket magazine, means including a manually operable lever for removing the share tickets separately and in sequential order from the magazine, and means for ejecting a share ticket each time the manually operated lever is moved manually in an arc in a forward or reverse direction respectively.
